CLAIM

The ornamental design for an ungulate shoe, as shown and described.

DESCRIPTION

FIG. 1 is a top perspective view of an ungulate shoe, showing our new design;

FIG. 2 is a bottom perspective view thereof;

FIG. 3 is a top view thereof;

FIG. 4 is a front view thereof;

FIG. 5 is a rear view thereof;

FIG. 6 is a bottom view thereof;

FIG. 7 is a left right view thereof;

FIG. 8 is a right left view thereof; and,

FIG. 9 is a cross-sectional view thereof, taken in the direction of line 9-9 in FIG. 4.
